FRANK ABRAM SICKLESTEEL AND CHARLES WESLEY BALLARD, OF
NORTHBRANCH, MICHIGAN.

MOLD FOR CONCRETE BLOCKS.

SPECIFICATION forming part of Letters Patent No. 737,032, dated August 25, 1903.

Application filed June 3, 1903. Serial No. 159,932. (No model.)

To all whom it may concern:

Be it known that we, FRANK ABRAM SICKLESTEEL and CHARLES WESLEY BALLARD, citizens of the United States, residing at 5 Northbranch, in the county of Lapeer and State of Michigan, have invented certain new and useful Improvements in Molds for Concrete Blocks; and we do hereby declare the following to be a full, clear, and exact description of the invention, such as will enable others skilled in the art to which it app pertains to make and use the same.

This invention is a mold for making cement blocks; and the improvements consist in certain constructions and combinations of parts whereby we produce a mold that is simple, compact, and that operates without the use of bolts or screws.

The invention further embodies an improved combined bed-plate and stripping-plate, together forming a guide or gage to assist in withdrawing the cores without marring the soft cement blocks.

Our invention is illustrated in the accompanying drawings, in which—

Figure 1 is a perspective view, broken away in parts, showing a mold with the combined base-plate and stripping-plate detached. Fig. 2 is a perspective detail of one of the removable inner walls of the mold.

As is clearly shown in the drawings, the mold consists in an outer rectangular frame 1, having neither top nor bottom. The inner face of the frame is beveled downwardly, so that the upper edge of each side member is narrower than the lower edge. Four separable side pieces 2, 2^a, 2^b, and 2^c are provided having vertical inner faces and beveled outside faces to fit the bevel of the frame 1. These four side pieces when in place interlock within the frame 1 and form the inner frame, within which the cement is packed. We prefer to construct the side members as shown in Fig. 2, casting them from iron or other suitable material, providing each piece with a number of downwardly-projecting beveled wings 2^c. This construction not only enables the side pieces to be made lighter, but also prevents liability of their binding in the frame 1 on account of small pieces of dirt or gravel becoming wedged

between the faces of the frame 1 and the side members.

The stripping-plate 3 is provided with suitable openings 3^b, through which cores 4^a and 4^{a'} project into the mold. In the outer face of the stripping-plate 3 are formed mortised channels 3^a and 3^{a'} to receive the cross-bars 4 and 4', carrying the cores 4^a and 4^{a'}. When in place, the mortised stripping-plate and cross-bars form a flush surface upon which the mold rests, and when the cores are being withdrawn the mortises 3^a serve as gages to enable the workmen to see at a glance whether the cross-bars 4, 4' are kept properly in line, and thus avoid liability of injuring the block by improperly withdrawing the core—a difficulty frequently met with where the cores are fastened to a base-plate of large area, because such a base-plate prevents the workman from seeing the core while it is being withdrawn.

Our construction enables each core to be withdrawn independent of the others, so that an accident in withdrawing one will not affect the remainder.

The operation of the mold is as follows: The outer frame is first set on the stripping-plate 3, the cores being in place. The side pieces 2, 2^a, 2^b, and 2^c are dropped into position so they fit snugly inside the outer frame. The mold is then filled with concrete and rammed, after which the top is struck off level. The mold is next inverted and the cross-pieces 4 and 4' are lifted up separately, as above described, bringing the cores with them. The cores strip themselves as they are drawn up through the openings 3^b in the stripping-plate 3. The removable bottom is next taken off, and the outer frame 1 is lifted up. This is easily done by reason of its beveled or wedge-shaped inside faces. The separable sides 2, 2^a, 2^b, and 2^c are left standing around the finished block and may be removed one by one.

The arrangement of parts is such that no lateral jar or strain is apt to be brought upon the soft block while the mold is being removed, and consequently a more uniform product is obtained than is possible when molds depending upon screws or clamps for their holding action are employed.

What we claim as our invention, and desire to secure by Letters Patent, is as follows:

In a mold for cement blocks the combination with the frame having downwardly-beveled inner faces; of a stripping-plate having core-openings and provided with mortises in its outer face in line with said core-openings; cross-bars removably seated in said mortises; cores fixed to said cross-bars and projecting into the mold through said core-openings; separable side members; and laterally-ex-

tending beveled flanges carried by said side members and adapted to register with the downwardly-beveled faces of the frame.

In testimony whereof we affix our signatures in presence of two witnesses.

FRANK ABRAM SICKLESTEEL.
CHARLES WESLEY BALLARD.
